UNITED STATES PATENT OFFICE.

WILLIAM GOLDIE, OF WEST BAY CITY, MICHIGAN.

TIE-PLATE.

SPECIFICATION forming part of Letters Patent No. 485,030, dated October 25, 1892.

Application filed March 17, 1892. Serial No. 425,289. (No model.)

To all whom it may concern:

Be it known that I, WILLIAM GOLDIE, a citizen of the United States, residing at West Bay City, in the county of Bay and State of Michigan, have invented certain new and useful Improvements in Tie-Plates, of which the following is a specification, reference being had therein to the accompanying drawings.

10 My present invention relates to improvements in tie-plates of the class in which the plate is composed of a thin strip or plate of metal introduced between the rail and tie and held in position by spikes passed through the plate and driven into the tie, the plate being especially arranged for receiving the chafing action of the rail, so as to prevent its cutting into the tie-surface.

The invention consists of a tie-plate having 20 a central portion provided with a transverse concavity in its upper surface to receive the rail and with a transversely-convex under surface having transverse ribs on each lateral side of the convex portion and with laterally-extending end portions having spike-openings adjacent to the edges of the central portion and provided on its upper side with a transverse rib with its inner edge coincident with the inner edge of the spike-opening; 25 and the invention also consists in a tie-plate adapted to rest upon the tie and carry the rail and provided on the portion beneath the rail with a depressed portion having a concave upper and convex under side; and the 30 invention also consists in the combination, arrangement, and construction of the parts and in the operation and effect of the same, as I shall presently proceed to describe in detail, and which will also be especially defined 35 and pointed out in the claims of this specification.

The object of my invention is to provide a tie-plate for resting between the rail and tie, in which the middle portion, which carries the 40 rail, will be supported in such a way as to avoid the common difficulty of depressing the middle portion and elevating the lateral portions by the action of the passing trains.

Another object is to so construct a thin tie-plate as to force its lateral end portions to rest upon the tie and to retain the plate

against a tendency to slide or move laterally upon the tie.

Another object is to arrange a tie-plate that can be made of a rolled-metal bar having the proper transverse contour by cutting transversely to the desired width and then 55 punching the required spike-openings.

My invention is fully illustrated in the accompanying drawings, in which the figures of 60 reference used in the following description will be found designating the same parts or elements throughout the several views.

Figure 1 is an isometrical view of my improved tie-plate detached. Fig. 2 is a transverse section of a railroad rail and tie and of 65 my improved tie-plate in position for carrying the rail. Fig. 3 is a plan view of the upper surface of the tie-plate. Fig. 4 is a plan view of the under side of the same. 70

1 represents a railway-tie, and 2 is the common T-rail resting on the tie.

3 is a tie-plate having a depressed central portion 4 beneath the rail and provided with a transverse concavity or depression 5 on its 75 upper side, while its lower side is provided with a transversely-convex surface 6 beneath the part 5. On each lateral side of the concavity 5 is arranged a plane surface 7, which receives the lateral portions of the base-flange 80 8 of the rail, and 9 is a transverse rib arranged across the upper side of the outer lateral portion 10 of the plate and with its inner edge resting against the outer edge of the rail-flange 8, and 11 is an opening cut through 85 the rib 9 and the plate, through which and into the tie a spike 12 is driven, the head 13 of the spike reaching over upon the rail-flange in the ordinary way for holding the rail upon the tie. The inner lateral portion 90 14 of the plate, which extends beyond the rail, is provided with an opening 15 for a spike 16, which is driven into the tie and with its head portion reaching upon the inner edge of the rail-flange. The under side of the portion 4 95 of the plate is provided directly beneath the parts 7 with transverse outstanding ribs 17, the outer faces 18 of which are provided with abrupt surfaces standing at a right angle with the under side of the plate, while the inner 100 faces 19 of the ribs are of a sloping form to provide a sharp edge at the angle of the two

sides, which cuts into and depresses the grain of the timber in the surface of the tie.

In practice the plates are placed between the rail and tie with the rib 9 bearing against 5 the lateral outer edge of the rail-flange 8, and the spikes 12 and 16 are then driven to hold the rail in position and to impress the ribs 17 into the tie-surface, and also to impress the convex surface 6 into the tie until the lateral 10 portions 10 and 14 of the plate rest firmly upon the tie-surface, the spike being again tightened down by driving to bring the parts to a firm position after a train has been passed over the road to firmly impress the 15 outstanding ribs and convex surface between into a solid and full bearing.

It is understood that when a rail of the ordinary T form is formed by rolling the form of the under surface of the base-flange of the 20 rail, and which rests upon the tie, is slightly raised in the middle of its width, owing to the clearance required to release the rail from the rolls, and with tie-plates of the ordinary form, having a straight or plane surface for receiving 25 the rail, the central portion of the thin plate is depressed slightly into the tie to bring its supporting-surface to conform to the fullness of the under surface of the rail, and this depression or bending of the plates causes 30 the lateral end portions thereof to rise from the tie, so that the plate really presents but little more surface for resting upon the tie than is covered by the bottom of the rail, whereas by forming the depression 5 and the 35 convex surface 6, as shown, beneath the rail the rail is caused to rest firmly upon the plate by the lateral portions of its under surface, and the convexity of the under side of the tie-plate causes the timber beneath the center 40 of the rail to be firmly compressed to a solid bearing, so that the action of the weight of the rail tends to straighten out the curve of the depressed central portion, and thereby transfers a portion of the strain or weight carried 45 by the plate to the lateral end portions, so that they are thereby held to snug contact with the tie-surface and form a firm and solid bearing for the rail, and prevent any canting or severing action of the rail.

50 It will be noticed that the full or depressed surface 6 depresses the fiber of the wood, so as to form a solidly-compressed section for supporting the middle of the convexity, so that any heavy strain placed upon the lateral 55 surfaces 7 will have a tendency to straighten out the curve of the depression until the under surface of the rail-flange comes to a full bearing on the plate, and this action going on gradually as the road is used allows the lateral end portions to retain their full bearing upon the tie after the road has been used for a long time, as when the full bearing of the 60 parts is obtained and the plate entirely conforms to its bearing on the tie the wood directly beneath the rail has become so compact and settled in place that slight changes only

in the form of the supporting-surface will obtain and a sure and reliable support for the rail is provided, and the plate being provided with the rib for contact with the outer lateral edge of the rail-flange and with the lower transverse ribs for entering the tie affords a great resistance against the lateral outward strain upon the rail exerted by the passing trains, so that a firm and solid support against 70 spreading the rails is provided, and at the same time a large area of surface is presented against the lateral outer edge of the rail-flange 75 to provide against chafing the neck of the spike.

It will be understood that the cheapest and most economical way to manufacture the tie-plate is to roll a blank bar to the proper thickness and with a transverse contour corresponding to the contour of the tie-plate and 85 then cut off the plates to the required width and punch the spike-holes in their proper position.

Of course it will be understood that the main and most important feature of my invention is the depressed portion for supporting the rail, and while I have illustrated the most convenient form and arrangement for general use, I do not limit my improvement entirely to the special arrangement of the 90 parts of the tie-plate shown, as very many minor changes in the several parts can easily be made and still produce the same general result and effect, and therefore—

I claim as my invention as follows:

1. A tie-plate for supporting railroad-rails and having a middle portion for carrying the rail and provided on its upper side with a transverse depression and with a transverse convexity on its under side and having lateral portions extending on each side of said middle portion and provided with spike-openings, substantially as set forth.

2. A tie-plate for supporting railroad-rails, having its middle portion bent transversely 110 to form a transverse depression on its upper side and a convex depression on its under side and provided with laterally-extending portions having spike-openings, substantially as set forth.

3. A plate for supporting railroad-rails upon the tie, and provided on its central portion beneath the rail with a depressed portion having a concave upper and a convex under side, and with laterally-extended portions for resting on the tie-surface, substantially as set forth.

4. A tie-plate for railroad-rails, consisting of a plate of metal having spike-holes on its lateral end portions and having a portion 125 between the spike-holes provided with a transversely-concave upper side and a convex under side, substantially as and for the purpose set forth.

5. The combination of a railroad rail and 130 tie with a tie-plate between the rail and tie and having its middle portion beneath the rail

provided with a transverse concave depression on its upper side presented toward the rail, and with a convex under surface and transverse ribs 17 embedded into the tie, and
5 with the rib 9 against the lateral outer edge of the rail-flange and having the lateral portions 10 and 14 resting on the tie and provided with spike-openings, and the spikes

driven through said openings and into the tie, substantially as set forth.

In testimony whereof I affix my signature in presence of two witnesses.

WILLIAM GOLDIE.
